CLAIM

The ornamental design for a shoe upper, as shown and described.

DESCRIPTION

FIG. 1 is a lateral side view of a shoe upper;

FIG. 2 is a medial side view thereof;

FIG. 3 is a front view thereof;

FIG. 4 is a rear view thereof;

FIG. 5 is a top plan view thereof;

FIG. 6 is a bottom plan view thereof; and,

FIG. 7 is a top perspective view from the lateral side thereof. The short, broken lines illustrate portions of an article of footwear including a shoe upper that form no part of the claimed design. The long, broken lines surrounded by solid lines illustrate stitching of the shoe upper that forms part of the claimed design.
